(57) **CLAIM**

The ornamental design for a notched container having an adjustable bracket, as shown.

DESCRIPTION

FIG. 1 is a rear perspective view of the notched container having an adjustable bracket of the present invention;
 FIG. 2 is a top perspective view thereof;
 FIG. 3 is a left side view thereof;
 FIG. 4 is a right side view thereof;
 FIG. 5 is a back view thereof;
 FIG. 6 is a front view thereof; and,
 FIG. 7 is a top plan view thereof.
